UNITED STATES PATENT OFFICE.

ALLEN B. COOKE, OF DANVILLE, ILLINOIS, ASSIGNOR TO UNITED AUTOGRAPHIC REGISTER COMPANY, OF CHICAGO, ILLINOIS, A CORPORATION OF ILLINOIS.

REGISTER.

Application filed July 29, 1925. Serial No. 46,714.

The present invention relates to registering devices of the type known in the trade as "autographic registers" and adapted to operate upon memorandum or data strips of indefinite length.

Among the objects of the invention is to provide a novel means for feeding the strips and for automatically stopping the feeding thereof at given intervals whereby sections thereof of given lengths may be severed and, if desired, also stored or filed. The feeding and severing means are preferably operated in time relation in accordance with the length of section used, and the severing is preferably automatically operated by the feeding means without the intervention of the human element, thus avoiding the possibility of failure to sever a section when a manual means might not be fully operated by an operator, as well as preventing the severing of a section at a too short a length by a premature manual operation of a severing means, as heretofore used.

The invention also comprehends the idea of automatically stopping the strips at the proper point and given intervals, irrespective of the use of different lengths of sections of strips and rendering the feeding mechanism inoperative to effect feeding of the strips for the remainder of the length of the sections, irrespective of the continued operation of the feeding means, the latter at such time operating idly. The driving means preferably has means for causing a dwell, such as mutilated gears, so that the driven feed members may be held inoperative for a part of the operation of the driving portion of the feeding means.

Another object of the invention is to provide a novel and simple means for automatically releasing the strip stopping means after the severing means has operated, thus avoiding the disadvantages incidental to the use of clutches and the like, which require fine adjustments and involve intricate and costly parts.

A further object is to provide a common means, operated by the feeding means, preferably during the dwell action, for actuating the severing or cutting means, the filing or storing means or pins and the kick-off means which releases or withdraws the free end of the section from the feeding means.

The invention also includes a novel feature for automatically initiating the feeding of the strips after the effecting of a severing of a section whereby the feeding operation may be resumed for a successive feed of the strips. This feature may be in common with the means for releasing the holding or stopping means, such as the hooks extending into the perforations of the strips, to permit the strips to be fed.

Other objects, advantages and capabilities are comprehended by the invention as will later appear and are inherently possessed by the invention.

Referring to the drawings, Figure 1 is a longitudinal vertical sectional view taken through a part of the register and in a plane represented by line 1-1 in Figure 3 of the drawings.

Figure 2 is a similar section in the same plane but showing the parts of the mechanism in a different position of operation.

Figure 3 is a transverse sectional view taken in a plane represented by line 3-3 in Figure 1 of the drawings.

Referring now more in detail to the drawings, the embodiment selected to illustrate the invention is shown as comprising a casing 1 having an end wall 2 to which is pivotally carried a cover 3 over a storing or filing chamber 4. At the other end of the device is a chamber 5 in which may be located one or more rolls of strip material and suitable let-off mechanism for letting off strips of material, such as memorandum or data carrying strips of paper 6, 7 and 8, these strips being fed over a table 9 forming a top member of the casing 1. These strips are provided at given intervals with perforations 11 and 12 which register in the respective strips.

The feeding mechanism comprises a manually operated crank 13 having a hub portion 14 suitably rotatably mounted in a bearing member 15 suitably secured to a side wall 16 of the device. To the hub 14 is rigidly secured a driving gear 17 in mesh with a driven gear 18 rotatably mounted upon a stud 19 suitably supported by members 20 secured to the side wall 16 and held in place by a nut 21. To the gear 18 is fixed to rotate therewith a mutilated gear 22 adapted to operate with a mutilated gear 23

secured to a shaft 24 having one end 25 thereof rotatably mounted in the hub 14 of the crank and the other end 26 thereof rotatably mounted in a bearing member 27 secured to the side 28 of the casing.

To the shaft 24 are secured a pair of driving or friction disks 29 and 30 adapted to engage with the under surface of the lower strip 8 of the material being fed through the machine. It will be noted that the mutilated gear has a dwell section thereof free of teeth on the pitch line of the gear, this section being adapted to cooperate with a toothless portion of the mutilated gear 23. It will be apparent that when the dwell portion engages with the member 39 the gear 23 will not be rotated, but that when the teeth of the gear 22 engages with the teeth of the gear 23, the former will drive the latter. In the specific construction illustrated, the gear 22 is adapted to drive the gear 23 through two revolutions for one revolution of the gear 23. For the purpose of permitting this, the gear 22 has a toothless portion 40 similar in construction to the dwell section 38 to properly cooperate with the member 39 when it is brought to a position midway of the length of the series of teeth on the gear 22.

30 The means for initially feeding the strips of paper comprises a friction or cam member 41 having a short peripheral surface 42 so located that when the shaft 24 is started to operate, the surface 42 will press against the under surface of the strips and by means of the friction thereof with the strip will initiate the feeding movement of the strips as is clearly shown in Figure 1 of the drawings. Above the strips of material is rotatably supported a knurled roll 43 having suitable bearings 44 and 45 secured to extensions 46 and 47 of the side walls 16 and 28. The cam member 41 is secured to the shaft 24 intermediate the ends thereof, and at one end 45 of the shaft 24 is secured a gear 48 meshing with a gear 49 secured to the shaft 50 of the roll 43, for the purpose of positively feeding the strips. After the member 41 has passed from the position shown in Figure 50 1 and after initiating the movement of the strips, further feeding is effected by the frictional engagement of the disks 29 and 30 with the under sheet or strip and the drive through the gears 48 and 49 and the roll 43 55 acting upon the upper strip of the group.

For the purpose of bringing the strips to a stop at the proper point, the strips are provided with perforations 11 and 12 at given intervals throughout the length of the strips. When any of the perforations, such as perforations 12 arrive between the roll 43 and the disks 29 and 30, a hook 51 carried by an arm 52 pivotally supported upon a pin 53 secured to a side wall of the casing, 60 65 will move upwardly into the perforations

under the action of a spring 57 connected to a fixed part of the casing top 9 and an arm 58 rigidly secured to the arm 52 as clearly shown in Figures 1 and 2 of the drawings. The hooks 51 will then act to prevent further movement of the strips and inasmuch as the peripheries of the disks 29 and 30 now operate into the space of the perforations, there is no tractive effect upon the strips and therefore the disks 29 and 30 will not effect or tend to effect a feeding movement thereof. The roller 43, if continued operation thereof is effected, will merely rotate idly over the top strip without effecting a feed thereof.

Upon the shaft 24 is also secured a cam 59 adapted to engage with the arm 58, as clearly shown in Figure 1 of the drawings, to depress the same and hence to release the hook 51 from the perforations in the strips. The action of this cam will occur at the time when the cam member 41 is brought into engagement with the under side of the lower strip when the initiating of the feeding is to be effected. In other words, the hook 51 is released just prior to the initiating feeding action of the cam 41, as above explained.

The strips of paper are so threaded through the mechanism that the lower strip 8 will pass through a guiding space between members 60, 61, 62 and 63 as clearly shown in Figure 2 of the drawings. These members may be secured at their ends in the side walls of the casing. The other strips, such as strips 6 and 7 may pass over the member 61 and to the exterior of the machine where they may be torn off and used as desired. The lower strip is to be severed at given lengths, and this is effected by a severing means or knife 64 having an upper cutting edge adapted to move upwardly through a cutting space 65 provided between the members 61 and 63 and 60 and 62. The lower end of the cutter 64 is adjustably connected to an arm 66 pivotally supported upon a cross pin 67 suitably mounted in the side walls of the casing. The cutter arm 66 is normally held against a cam 68 secured or made rigid with the gear 22, by means of a spring 69 secured at one end to the arm 66 and at the other end to a fixed part 70 of a side wall of the casing.

To the other end of the arm 66 is pivotally connected a depending link 71 having an offset portion 72 having its lower end 73 reciprocably slidable in a guide member 74 suitably secured as by screws 75 to the bottom wall of the casing. The link has a beveled laterally extending arm 76 capable of cooperating with a beveled arm 77 pivotally supported upon a cross pin 78 secured in the side walls of the casing. The arm 77 has a slot 79 in which is received a pin 80 secured to a hub of a kick-off member 81 extending upwardly and having at its free end a kick-off

finger 82. Two of these kick-off devices are preferably provided to engage with both sides of a section of paper that has been severed from the under strip 8. It will be noted that the arm 77 is capable of a limited upward movement when the member 76 is raised, but when the latter is lowered, it may engage with the member 77, and by reason of the connection through the pin 80 the downward movement of the member 77 will cause the lateral movement of the kick-off member 81 to the right as shown in Figure 2 of the drawings, a part of this position being shown in dotted lines in this figure, as well as showing the free end 83 of the severed section of the lower strip 8. The kick-off members are returned to normal position by a spring 84 connected at one end to the member 81 and to a fixed part 85 secured to the casing 1. The return movement of the member 81 is limited by a stop 86 also secured to a part of the casing.

As the lower strip is fed through the guiding means, it will pass downwardly through the members 63 and 62 and the perforations thereof will move into a position where filing pins 87 may enter through the perforations whereby the severed section may then, when severed, be automatically filed on these pins. These pins are curved and are rigid with a cross pin 88 rotatably mounted at their ends in the side walls of the casing. The upper ends 89 of the pins are tapered so that they will readily enter into the perforations of the section 8 as it descends from between the members 62 and 63. The lower end of the pins 87 are pivotally connected to links 90 connected pivotally to a lever 91 pivotally mounted by means of pins 92 in a supporting member 93 secured to the bottom of the casing. The free end 94 of the lever 91 bears against the cam 68 as clearly shown in the drawings. This lever 91 is normally held in engagement with the cam and the pins 87 are normally held in the position shown in Figure 2, by means of a spring 95 connected at one end to a pivot pin 96 forming the pivot for the lower end of the filing pins 87 and the link 90, and the other end of the spring 95 is secured to a fixed member 97 fastened to the bottom wall of the casing.

A cover 100 may be provided for the roll 43 as desired.

In the operation of the device, the strips 6, 55 7 and 8 are first arranged so that the perforations 11 or 12 may be in registry and are threaded between the feed rollers so that the lower strip 8 will pass into the passage between the members 60 and 61 and the upper strip may pass to the exterior of the device. The crank mechanism may then be operated so as to cause the gear 17 to drive the gear 18 which, being rigidly fastened to the gear 22, will drive the latter to the point that its teeth 60 may engage with the teeth of the gear 23.

The gear 22 will rotate in the direction of the arrow 101 and the gear 23 will rotate in the direction of the arrow 102. The starting operation is shown in Figure 1 of the drawings. In this position the gear 23 has started to move with the cam 41 which engages with the lower strip and presses the strips against the roller 43 and thus initiates the movement of the strips to the right as viewed in Figures 1 and 2 of the drawings. At this point of operation the cam 59 has engaged the arm 58 so as to withdraw the hooks 52 from the perforations. The strips are now free to be fed forward. Further rotation will cause the strips to move with the lower strip passing through the throat of the members 60, 61, 62 and 63, and descend into position for engagement by the ends of the filing hooks. During this operation the cam 68 is moving to permit the movement of the lever 91 to the right, and hence a movement of the filing pins 87 to the left, from the full line to the dotted line positions shown thereof in Figure 1 of the drawings. As the perforations approach the ends of the filing pins, the ends 89 of these pins will enter through these perforations and the forward end of the section 8 will pass down over the pins 87.

During this operation the cam 59 shall have passed off of the arm 58 and permitted the hook 51 to move upward against the under surface of the lower sheet of material, and the cam 41 shall have passed from this lower sheet and the disks 29 and 30 will be operated with the roll 43 to continue the feeding of the strips. This feeding operation will continue until the succeeding perforations have arrived to the position shown in Figure 2 of the drawings. As soon as the perforations arrive at this point, the hooks 51 will move upwardly into the perforations under the influence of the spring 57. These hooks will then prevent the further feeding of the paper notwithstanding the continued rotation of the disks 29 and 30. The gear 22 will then arrive at a position where the dwell section 38 will engage or cooperate with the dwell portion 39 of the gear 23 and stop the further rotation of the shaft 24 and the parts connected thereto. During the dwell operation, the cam 68 having the lobe 107 will engage with the arm 66 and raise the same, and hence the cutter 64 which will pass through the cutting opening 65 and sever the sheet of material extending in the throat between the members 60 and 61, and 60 and 63. During the upward movement of the arm 66 the link 71 will rise and the tapered end of the member 76 will lift the member 77 but will not cause a movement of the member 81, owing to the loose play permitted between the slot 79 and the pin 80. As the cam 68 and its lobe 107 continues its rotation, the arm 66 will be permitted to move downward with the link 71 and the arm 76 will engage with the arm 130

77 and by reason of the pin 80 being at the upper end of the slot 79, the arm 77 will effect the movement of the arm 81. The fingers 82 of these arms will engage with the rear of the severed section 8 and move the same from the full line position to the dotted line position shown in Figure 2 of the drawings. This is a kick-off operation so as to release or withdraw the free end of the severed section from 10 the guiding members 62 and 63. At this point of operation the cutter 64 shall have moved downwardly to its original position. As the member 76 slips off of the end of the member 77, the spring 84 will immediately retract 15 the members 81 to the full line position shown in Figure 2. The severed section will then fall horizontally into the positions shown thereof in Figure 1 of the drawings which show three sections already in filed position 20 on the filing pins 87. The gear 22 shall now have passed through its dwell period and its teeth will again engage with the gear 23 and start the movement of the shaft 24 so as to bring the cam 59 against the arm 58 so as to 25 release the hooks 51 from the perforations and cause the cam 41 to initiate a feeding movement by contact with the under side of the lower strip of the group of strips being fed. Further operation will be similar to that 30 already explained.

From the description given, it will be understood that as the strips are being fed over the platen, the advance end of the lowermost strip being discharged is deflected downwardly into the inner end-portion of the filing compartment, and the filing pins are caused to protrude through the advance end of the strip-portion, or triplicate sales-slip; and, as the operation continues, the impaling pins 35 of the filing device serve to guide the advance end of the slip downwardly; and, at the proper time, the slip-overturning device comprising the arm 81 operates to bring the lateral extensions 82 into engagement with the back side of the slip and effect the positive 40 over-ending of the sales-slip and the proper deposit thereof, in inverted position, upon the accumulating stack of slips, it being understood that the slip being filed is, at the proper time, severed from the body of the 45 strip. The invention, in the broadest aspect of this phase, contemplates suitable means for effecting severance of the slip, or slips, to be filed and overturning and depositing the slips in the filing compartment, thus gaining 50 the advantage of a stack of inverted slips which has been noted above; and, in the preferred embodiment of the invention, thus stated, which is described in the present application, a device is provided which automatically engages the back side of the slip to be filed at a distance from the impaling pins 55 and effects the positive kick-over of the slip, insuring the deposit of the slip in flat condition upon the accumulating stack of slips. 60

While, in the embodiment shown, provision is made for filing the lowermost strip, the invention is not limited thereto.

The foregoing detailed description has been given for clearness of understanding only, and no unnecessary limitations should be understood therefrom, but the appended claims should be construed as broadly as permissible, in view of the prior art.

Having thus disclosed my invention, I claim:

1. In a device of the character set forth, a platen, means for feeding strips thereover, an impaling pin adapted to impale the advance end of a strip from the face side, severing means, and movable means adapted to engage and overturn the impaled section.

2. In a device of the character set forth, in combination with a platen and means for feeding strips thereover, an impaling pin adapted to extend through the advance end of a strip from the face thereof, and means for engaging the back surface of the impaled section and effecting positive overturning and deposit of said section in the filing compartment.

3. In a device of the character set forth, in combination with a platen and means for feeding strips thereover, means for deflecting the advance end of a strip downwardly into the inner end-portion of the filing compartment, an impaling pin adapted to be protruded through the advance end of said strip from the face side thereof, automatically actuated means for actuating said impaling pin, and automatically actuated means adapted to engage the back face of the deflected section and effect positive overturning and depositing thereof.

4. In an autographic register comprising a web receiving platen, a source of web supply for the platen, means for feeding the web over and beyond the platen, a filing device adapted to receive and file the portions of the web as they are projected beyond the platen, and a web severing device operatively connected with the feeding means, adapted to cut each projected portion of the web from its source of supply after the projected portion has been engaged by the filing device.

5. An autographic register comprising a web receiving platen, a source of web supply for the platen, means for adjusting the platen supported portion of the web relatively to the platen, means for feeding the web over and beyond the platen and to condition it for adjustment by said adjusting means, a filing device adapted to receive and to file the portions of the web projected beyond the platen, and a web severing device operatively connected with the feeding device, adapted to cut each projected portion of the web from its source of supply after the feeding operation has been completed, cessation of the feeding operation permitting the previously

conditioned web to be adjusted before the cutting operation.

6. A web severing and filing device for registers, comprising a support for a web, a web feeding mechanism, an aligning pin adapted to engage a perforation in the web for adjusting the position of a portion of the web relatively to the support, a knife for severing the web operatively connected with the web feeding mechanism for operation after the feeding operation has been completed, and a filing pin adjacent to the knife, adapted to engage the web perforation previously engaged by the aligning pin and brought into function during operation of the feeding device and before operation of the knife.

7. In an autographic register in which a paper strip is intermittently advanced, impaled upon a filing-pin and severed into tickets, an arm pivotally mounted in the register having a lateral portion adapted to engage the impaled ticket, and cam means actuated by the advancing mechanism for moving said arm whereby the lateral portion thereof inverts the impaled ticket and deposits the latter in a filing space.

8. In an autographic register in which a paper strip is intermittently advanced, impaled upon a filing pin and severed into tickets, an arm pivotally mounted in the register adapted to engage the impaled ticket, and means actuated by the advancing mechanism for moving said arm whereby to invert the impaled ticket and deposit the latter in a filing space.

9. In a machine of the character set forth, a platen, strip-feeding mechanism adapted to engage punch-holes in strips fed across said platen and thereby discontinue the feed, means for initiating the strip-feeding operation, a filing device having an impaling-pin adapted to engage a punch-hole previously engaged by the strip-feeding mechanism, means actuated in timed relation with respect to said strip-feeding mechanism for actuating said impaling-pin, and means for deflecting a strip as it is being projected from the platen by said strip-feeding mechanism to bring the punch-hole of the strip into position to be engaged by said impaling-pin.

10. In a machine of the character set forth, a platen, a filing-compartment back of said

platen, strip-feeding mechanism between said platen and said compartment adapted to draw strips across the platen and project a strip into said compartment, means for deflecting the advance end of a strip downwardly into the front portion of said compartment, an impaling-pin in said compartment adapted to be inserted through the advance portion of the deflected strip from the face side of the strip, actuating means for said impaling-pin timed with relation to said strip-feeding mechanism to cause the impaling-pin to impale the advance end of the strip and guide it downwardly while the strip-feeding mechanism projects the strip into said compartment, and means for effecting severance of the impaled slip from the strip at the conclusion of the strip-feeding operation.

11. In a register adapted for use in connection with strips comprising forms having filing perforations near the advance ends of the forms, a platen, normal strip-feeding mechanism adapted to operate idly upon encountering the filing perforations, means for initiating a strip-feeding operation, register-pins adapted to engage the filing perforations at about the conclusion of the strip-feeding operation, a filing-compartment back of the strip-feeding mechanism, means for deflecting a strip into said compartment as it is being fed from the platen, an impaling-pin adapted to engage a filing perforation previously engaged by a register-pin, means for actuating said impaling-pin timed to cause the impaling-pin to engage the filing perforation, and means for effecting severance of the impaled slip from the strip subsequent to the strip-feeding operation.

12. In a register of the character set forth, a platen, strip-feeding mechanism, a filing-compartment equipped with an impaling device timed with respect to said strip-feeding mechanism and operative to impale a strip while it is being projected by said strip-feeding mechanism into said compartment, and means for separating the impaled slip from the strip subsequent to the strip-feeding operation.

In witness whereof, I hereunto subscribe my name to this specification.

ALLEN B. COOKE.
